UNITED STATES PATENT OFFICE

2,002,545

WATER HEATING SYSTEM

Virgil Moray, New York, N. Y.

Application October 6, 1933, Serial No. 692,536

4 Claims. (Cl. 122—32)

My invention relates to steam boilers and more specifically to improvements in method of and apparatus for adapting steam boilers to the work of heating water for domestic use, or the like.

- 5 It has long been common practice to install submerged water heating coils in steam boilers in such manner that the effective heating surface of the coil is limited to that portion of its length which extends within the steam boiler.
- 10 Where the steam boiler is not of sufficient length or width to permit the installation of a coil of a required length the common practice is to insert one or more additional coils in order to obtain a required amount of coil heating surface.
- 15 One of the objects of my invention is to provide means by which the effective length of a coil submerged in the water of a steam boiler may be very substantially increased and whereby the expense and trouble of installing one or
- 20 more additional coils may be avoided.

25 Further objects and advantages of my invention will be apparent from the following description considered in connection with the accompanying drawing, which forms a part of this specification and of which:

Fig. 1 is a cross-sectional view of a preferred embodiment of my invention; and

Fig. 2 is a cross-sectional view taken on the line 2—2 of Fig. 1.

- 30 Referring to the drawing, reference character 10 designates a steam boiler in which the water level is maintained at line 11. The steam is withdrawn through main 12. Fire tubes 13 extend through the water space and the hot flue gases passing therethrough heat the water. Fire tubes 13 communicate with a fire box 14 in which is a grate 15. Welded into an incision formed in steam boiler 10 is the hollow sleeve 16, an integral part of which is the flange 17 to which is bolted the coil head 18 by means of a flange 19 integral with coil head 18, and bolts 20. A gasket 21 is interposed between flanges 17 and 19. Coil head 18 is formed with an inlet chamber 22 and an outlet chamber 23. A plurality of U-shaped water heating coils 24 have their ends connected to chambers 22 and 23, respectively. The upper portion of coils 24 are positioned just below the water level 11 in order that they will be contacted by the hottest water in the boiler 10.
- 35 Sleeve 16 is so dimensioned as to leave a sufficient space for unimpeded circulation of boiler water between it and coils 24 extending therethrough. Connecting the inlet chamber 22 in coil head 18 with the source of water to be heated is the pipe 25. Connecting the outlet chamber 23

in coil head 18 with a suitable hot water storage tank or directly with the hot water consumers is the pipe 26.

The operation of the above described system is as follows:

Water to be heated is admitted through pipe 25 to inlet chamber 22 in coil head 18 from where it passes through heating coils 24 to outlet chamber 23 and thence through pipe 26 to storage or use. The water within boiler 10 is heated by contact with fire tubes 13 and this heated water rises to the surface, where it contacts coils 24. Consequently, the portions of the coils which extend into the boiler proper are contacted by the hottest water in the boiler. As 15 to the portions of the coils within the sleeve 16, a good heat transfer is obtained by virtue of the fact that a rapid circulation of hot water thereover is maintained. Inasmuch as the coldest water enters the lower passes of the coils, this cools 20 the water within sleeve 16 and causes it to drop down in the path indicated generally by arrow 27. Hot water flows into sleeve 16 along the path indicated generally by arrow 28 and replaces the cooled water. Thus a constant circulation of hot 25 water into sleeve 16 is maintained and most efficient use is made of the heating surface of coils 24 within the sleeve. As previously pointed out, sleeve 16 is made large enough to permit this circulation. Also, the sleeve is preferably sub- 30 stantially rectangular in cross-section, as shown in Fig. 2, in order that the space under the different tubes will be about equal. This gives more uniform flow, but if desired, a cylindrical sleeve may be employed.

35 Thus it is apparent that the heating coils 24 are of considerably greater length than the dimensions of boiler 10 would normally permit and furthermore, that the entire surface of the tubes is effective for heat transfer purposes.

40 While I have shown and described only one embodiment of my invention inasmuch as this is sufficient for a clear understanding of it, the scope is not intended to be limited thereby, but is to be determined by the appended claims viewed 45 in the light of the prior art.

What I claim is:—

1. In combination, a boiler having walls, including side walls, defining a water space, fire tubes extending through said space substantially 50 parallel to said side walls, a hollow member secured within an opening formed in one of said side walls, and water heating tubes of substantially greater length than the width of said boiler positioned within said hollow member and ex- 55

tending into said water space substantially at right angles to said fire tubes.

2. In combination, a boiler having walls, including side walls, defining a water space, fire tubes extending through said space substantially parallel to said side walls, a hollow member secured within an opening formed in one of said side walls, and water heating tubes of substantially greater length than the width of said boiler positioned within said hollow member and extending into said water space substantially at right angles to said fire tubes, said hollow member being so dimensioned as to provide sufficient space around said tubes for the circulation of water from said water space.
3. In combination, a boiler having walls, including side walls, defining a water space, fire tubes extending through said space substantially parallel to said side walls, a substantially rectangular hollow member secured within an opening formed in one of said side walls, and water heating tubes of substantially greater length than the width of said boiler positioned within said hollow member and extending into said water

space substantially at right angles to said fire tubes, said hollow member being so dimensioned as to provide sufficient space around said tubes for the uniform circulation over the various tubes of water from said water space.

4. In combination, a boiler having walls, including side walls defining a water space, fire tubes extending through said space substantially parallel to said side walls, a hollow member secured within an opening formed in one of said side walls, water heating tubes of substantially greater length than the width of said boiler positioned within said hollow member and extending into said water space substantially at right angles to said fire tubes, said hollow member being so dimensioned as to provide sufficient space, around said tubes for the circulation of water from said water space, and means for introducing the water to be heated first into a portion of said tubes within said hollow member, whereby the water within said member is cooled and circulation produced.

VIRGIL MORAY.
